UNITED STATES PATENT OFFICE.

LIPA POLINKOWSKY, OF LONDON, ENGLAND, ASSIGNOR TO WESTERN ELECTRIC COMPANY, INCORPORATED, OF NEW YORK, N. Y., A CORPORATION OF NEW YORK.

MACHINE-SWITCHING TELEPHONE SYSTEM.

1,412,572.

Specification of Letters Patent. •Patented Apr. 11, 1922.

Application filed December 6, 1918. Serial No. 265,600.

To all whom it may concern:

Be it known that I, LIPA POLINKOWSKY, a citizen of Russia, residing at 70 Westbourne Terrace, Hyde Park, London, W., England, have invented certain new and useful Improvements in Machine-Switching Telephone Systems, of which the following is a full, clear, concise, and exact description.

This invention relates to machine switching telephone systems and more particularly to machine switching telephone systems of the semi-automatic type in which calls are extended over operators' positions on which the calls receive full supervision.

15 A feature of the invention is the provision of circuits and apparatus for enabling the calls initiated, during the slack or non-busy hours, at a small exchange located in the same area as a large exchange, to be automatically extended to an operator's position at such large exchange.

Another feature of the invention is the provision of means for converting some of the trunk lines extending between the large 25 and small exchange, from the ordinary day service trunks to slack or non-busy hour service trunks.

Still another feature of the invention is the provision of circuits and apparatus to convert some of the switches used in the small exchange for day service, into switches suitable for extending calls to an operator's position at the large exchange.

A still further feature of the invention, 35 and one related to the last named feature, is the provision of circuits and apparatus for so converting the switches of the small exchange, which give full supervision, including release under control of the operator at the small exchange, that full supervision, 40 including release, of a call initiated at the small exchange and extended to an operator's position at the large exchange, is given by the operator at such large exchange.

45 A further feature of the invention is the provision of circuits and apparatus for automatically testing, at the initiation of the conversion, the condition existing on the trunks and switches and to postpone the conversion of a trunk or switch as long as a connection exists thereon.

Still another feature of the invention, and one relating to the above last named feature, is an arrangement of circuits and apparatus to automatically test the ends of the

trunks at the large exchange, simultaneously with the testing of the trunks at the small exchange, and to delay also the conversion, in the large exchange, of a trunk until such trunk becomes free.

60 A particular feature of the invention is the provision of means for automatically initiating the conversion of the trunks and switches from day to night service when all the operator's positions at the small exchange are vacant, and to automatically restore the trunks and switches from night service to day service when an operator's position at the small exchange is placed in service.

70 Fig. 1 shows a subscriber's line and a first line finder.

Fig. 2 shows a cord consisting of a second line finder and a first group selector.

75 Fig. 3 shows the searching sequence switch of the cord and an operator's position indicated so far as is essential for the understanding of the system.

Fig. 4 shows a common arrangement which controls the necessary change over from day 80 service to night service in the exchange.

Fig. 5 shows the arrangement for the change over required in the distant main exchange.

85 Fig. 6 shows a modification in which separate second line finders are used for night service.

90 Fig. 7 shows a modification in which the introduction of the night service is made automatically when all operators' positions in the exchange are vacant and is automatically removed as soon as one of the positions is occupied by an operator.

95 Fig. 8 shows a cord used for day service only.

Figure 9 shows a diagram of two exchanges and interconnecting trunks.

The system disclosed as embodied in the present invention will be best understood from a description of the operation thereof and reference to United States Patent No. 1,160,181, of November 16, 1915, to F. R. Mc-Berty and D. Koenig, and United States Patent No. 1,193,053, of August 1, 1916, to L. Polinkowsky, fully describing the analogous circuits disclosed in the present invention.

In order to enable, during the night, the use of second line finders and trunk lines which are also used during the day, the cir- 110

cuit of several cords in the small exchange, sufficient to carry the night service, is modified by the addition of a sequence switch 100 to each such cord. The operation of a cord 5 so far as day service is concerned is the same as for night service the only difference being that in several points the circuit is maintained closed over contacts of the special sequence switch 100.

10 The contacts of this sequence switch are differentiated from the contacts of sequence switches 220 and 250 by showing them solid. Further the contacts and relays associated with the sequence switch 100 are designated 15 by numbers in the one hundred group of numerals.

During the day sequence switch 100 is in position 1 and its contacts remain without influence on the operation of the cord which is, 20 briefly stated, such that a line relay 201 is operated and causes the operation of the common starting relays 204; the power magnets 211 of the free first line finders in the group are energized and the line finders 25 search for terminal 210 of the line, in reaching which test relays 214 and 212 of the line finder are energized; the power magnet 211 is disconnected and the holding magnet 215, together with the common starting relays 30 216, is energized. At the free cords, the line finders of which have access to these first line finders, the relays 252 are energized and cause the energization of the power magnets 261 so that the brush carriages of the second line finders rotate and the test relays 264 and 35 262 of the line finder which first reaches the terminal 230 are energized, disconnecting the power magnet 261 and energizing the holding magnet 265. Sequence switch 250 of the 40 cord is also energized, starts from position 1 and moves into position 4. In passing position 21 sequence switch 220 of the cord is also energized, starts from position 1 and moves into position 4. Relay 227 is thereby 45 energized together with relay 213 of the first line finder and the cut-off relay 207 of the subscriber's line. The left-hand windings of the repeating coil 229 and the supervisory relay 231 are brought into circuit with the 50 calling line, and the calling lamp 270 together with pilot lamp 372 are lighted. Sequence switch 330 is now energized and searches for a connection with a free register of the operator's position and, assuming the 55 A register free, is arrested in its position 1 or 7 in which the test relays 264 and 262 are again energized and sequence switch 250 moves from position 4 over position 5 into position 8. When sequence switch 250 passes 60 position 6 sequence switch 220 is again energized and moves from position 4 into position 5. The calling lamp 270 is thereby connected with an interrupter 236 and displays a flashing signal before the operator. The 65 operator's telephone is now connected in

bridge to the calling line. When the operator depresses the number keys, not shown, according to the number required, sequence switch 220 moves out from position 5 into position 8, in which the ringing lamp 240 displays a flashing signal. The fundamental circuit containing the stepping relay 324 of a register is first closed over relay 252 which is energized and causes the advance of sequence switch 250 into position 9 in which the 75 trip spindle 273 rotates. At its contact 275 short-circuitings are provided to the fundamental circuit and after the first series of impulses is completed relay 252 is de-energized and sequence switch 250 advances from 80 position 9 into position 10 in which the test relays 264 and 262 are brought in connection with brush 276 of the first group selector, whereas the power magnet 281 of the selector brush carriage is energized and the brushes 85 are moved along the terminals in the row determined by the position of the trip spindle. Relay 252 is thereby maintained energized over the register circuit. After finding a free second selector the test relays 264 and 90 262 are energized, the power magnet 281 is disconnected, while the holding magnet 285 and sequence switch 250 are energized. Sequence switch 250 is advanced from position 10 over position 11 into position 12 in which 95 the fundamental circuit is extended to the second group selector. After the completion of the selection the register is released and relay 252 is de-energized;—sequence switch 250 moves into position 14. When the sequence switch of the final selector used for 100 this connection is passing over its busy position, supervisory relay 242 is energized and sequence switch 220 moves from position 8 into position 9 and when the sequence switch 105 of the final selector leaves the busy position, relay 242 is de-energized and sequence switch 220 moves from position 9 into position 11 in which the ringing lamp 240 lights. When the called subscriber answers and a through 110 connection is established at the final selector, the right-hand windings of the repeating coil 229 and relay 242 are brought in connection with the called line, relay 242 is again 115 energized and the sequence switch 220 moves 120 into position 14. After the conversation is completed and the clearing out signals 225 and 245 are displayed before the operator she depresses the release key 280 of the cord and causes the energization of release relay 263 125 which in turn causes sequence switch 250 to move from position 14 into position 17. When sequence switch 250 reaches position 15 the sequence switch 220 is started and moves from position 14 into position 1. In 125 passing positions 16 to 18 the metering battery 359 is connected to the calling line and the meter 208 is operated. When sequence switch 220 reaches position 18 relay 252 is energized and causes the advance of sequence 130

switch 250 from position 17 into position 18 in which the brush carriage is restored to its position of rest, whereby after the home contact 289 of the brush carriage is closed relay 262 is energized together with the holding magnet 285 and sequence switch 250 moves into position 1.

If the called line is busy relay 242 remains continuously energized and sequence switch 220 remains in position 9 in which the lamp 235 is connected to an interrupter 246 over contact 248, bottom, in position 9 and displays a busy signal before the operator. The secondary winding of the common busy tone coil 247 is connected in bridge to the line and the operator in depressing the listening key 239 can communicate with the subscriber. She releases the connection, after the subscriber has restored his receiver, by depressing release key 280 to energize relay 263 and causes sequence switch 250 to move into position 17 and open the circuit for relay 227 before sequence switch 220 leaves position 15 causing the energization of relay 224 which hinders the metering. The metering is also hindered if the release is made when sequence switch 220 is in the ringing position 11 and the called subscriber does not answer. To force the release of a connection on which relay 231 is energized over the calling line, the operator depresses the release key 280 of the cord and the forced release key 375 at her position. To bring the switches of the connection in a holdover condition, whereby the calling line is made free, the operator depresses the listening key 239 on the cord and the common holdover key 365. Relay 225 is thereby energized, the sequence switches individual to the switches used for a connection are advanced into position in which the switches are held up, whereas the calling line is made free. When the operator desires to hinder the metering of a successfully established connection, due to the complaint of the subscriber, she depresses the common metering-hindering key 364 before depressing the individual release key 280 and the metering battery 359 is disconnected during the release.

For night service key 420, Fig. 4, is depressed and the common sequence switch 400 is energized, in a circuit over contact 406 top and contact of key 420. Sequence switch 400 starts from position 1 and moves under the control of its local contact 401 into position 10. When sequence switch 400 reaches position 2 each sequence switch 100 individual to a cord used during the night service is energized in a circuit over its contacts 105 top and a contact of sequence switch 400 corresponding to contact 402 top. Sequence switch 100 starts from position 1 and moves under the control of its local contact 101 into position 2. In position 2 of sequence

switch 400 relay 479 at the main exchange is also energized over a separate trunk 430 and contact 403 of sequence switch 400. Relay 479 causes the energization of sequence switch 460 over contact 462 bottom and front contact of relay 479. Sequence switch 460 starts from position 1 and moves under the control of its local contact 461 into position 2. In position 2 of sequence switches 100 and 460 a test is made to determine whether or not trunk lines which are to be used for night service are involved in a connection. One sequence switch 460 is used in the distant main exchange for several trunk lines. Each trunk line is provided with a relay 463 which is connected over contact 464 of sequence switch 460 in position 1 to the test terminal 465 and if the trunk line is busy relay 463 is energized and maintains its connection over its right-hand front contact. If all the trunk lines controlled by sequence switch 460 are free a circuit is established for the energization of sequence switch 460 over contact 466 and the left-hand back contacts of relay 463 and the corresponding relays 467 and 468 of the remaining trunk lines. Sequence switch 460 then starts from position 2 and moves into position 10 in which over contacts 469 and 470, the trunk line is connected to the terminals of a group of second line finders and to a line relay 471. The second line finder in the main exchange belongs to a cord arranged in the same way as the cords in the smaller exchange used for day service only. Such a cord is shown in Fig. 8. The cord is connected to an operator's position in the same way as indicated in Fig. 4. A comparison of Fig. 1 with Fig. 8 will make clear the difference in the circuit of the cords specially arranged in the smaller exchange for night service. In position 2 of sequence switch 460 Fig. 5 a circuit is closed for the energization of sequence switch 490 over contact 481, top, of sequence switch 460 and contact 492, bottom, of sequence switch 490. Sequence switch 490, which controls further trunk lines, starts from position 1 and moves into position 2 in which over its contact 496 top a similar test is made to determine whether or not the corresponding trunk lines are free, after which sequence switch 490 moves into position 10. Sequence switch 100 when in position 1 connects, over its contacts 102 and 103, the line finder of the cord to the other end of the trunk line, whereby for night service a part of the trunk lines is preferably used over which in the day connections are established outgoing from the main exchange to the small exchange. Conductors 151 and 152 indicate the connection to a second group selector used on the incoming end of a trunk. It is essential that sequence switch 100 shall not move into position 10 and en-

able the line finder to obtain a connection with a calling line unless and until the sequence switch 460 used for several trunk lines has also been advanced to position 10. Sequence switch 100 therefore in position 2 undertakes a test as to whether not only the trunk line 450 but also the other trunk lines controlled by the sequence switch 460 are free, which is the case if their sequence switches are in position 1; sequence switch 100 is then energized in a circuit over contact 104 top and contacts 440, 441 and 442 of the individual sequence switches of the second group selectors on the incoming end 15 of these trunk lines. Sequence switch 100 starts from position 2 and moves into position 10 providing thereby a number of changes in the circuit of the cord. Several contacts on sequence switch 400 are also utilized to aid in the changes required: at contact 404 of sequence switch 400 the common conductor 306, which connects the calling lamps 270 of the cords to the pilot relay 358 of the operator's position is opened and at 20 contacts similar to contact 405 the connections from the common starting relays 216 of the first line finder groups to the relays 252 of the corresponding cords are closed, re-establishing over wires 431 and 432 the 25 circuits which are kept opened at contacts similar to contact 352 of the timing sequence switch 350 of the operator's position in position 12. The number of contacts similar to contact 405 of sequence switch 400 is equal 30 to the number of cord groups, each having access to sixty first line finders, whereas the number of contacts similar to contact 402 is equal to the number of cords used for the night service, whereby only a few cords in 35 each group are sufficient during the night for each sixty first line finders.

At contact 106 top of sequence switch 100 in position 10 the left-hand high resistance winding of relay 264 is disconnected from 40 contacts 353 of the timing sequence switch 350 and connected to contact 255 bottom of sequence switch 250, re-establishing the connection opened at contact 353 of sequence switch 350 in position 12.

When the brush carriage of a first line 45 finder is arrested on the terminals of a calling line and the starting relays 216 are energized, relays 252 of each free cord which has access to this first line finder are energized in a circuit over the contact 253 of sequence switches 250, conductor 432, contact 405 of sequence switch 400, conductor 431, and front contacts of common starting relays 216. The power magnet 261 of the second 50 line finder is thereby energized in a circuit over contact 254 top of sequence switch 250, back contact of test relay 262 and front contact of relay 252. The brush carriage of the second line finder rotates. When the 55 terminal 230 of the calling first line finder is reached, relay 264 is energized in a circuit including contact 255 bottom of sequence switch 250, contact 106 top of sequence switch 100, left-hand high resistance winding of relay 264, contact 256 of sequence switch 250, terminal 230, resistance 217, front contact of relay 212 and back contact of relay 213. Relay 264 brings, over its front contact, its right-hand low resistance winding together with winding of relay 262 in parallel to its high resistance winding. Terminal 230 is made busy and relay 262 is energized. The power magnet 261 is disconnected on back contact of this relay whereas over its front contact is caused the energization of sequence switch 250 in a circuit including contact 257 bottom of sequence switch 250 and front contacts of relays 262 and 252. In parallel to the sequence switch is also connected over its contact 260 the holding magnet 265 of the line finder, the brush carriage is arrested, whereas sequence switch 250 starts from position 1 and moves under the control of its local contact 251 into position 4. The energization of relay 349 in parallel to magnet 265 remains without effect on the timing sequence switch 350, which is not in its position 1. When sequence switch 250 passes over position 2, a circuit is established for the energization of sequence switch 220 over contact 222 bottom, contact 266 bottom of sequence switch 250, left-hand back contact of release relay 263 and contact 258 top of sequence switch 250. Sequence switch 220 starts from position 1 and moves into position 4. In position 2 of sequence switch 220 a circuit is established for the energization of cut-off relay 207 of the subscribers line, relay 213 of the first line finder and relay 227 of the second line finder, including terminals 218 and 228, left-hand back contact of holdover relay 225, right-hand back contact of metering-hindering relay 224, contact 223 of sequence switch 220, right-hand back contact of metering relay 123, right-hand back contact of relay 263 and contact 255 top of sequence switch 250. The line relay 201 is de-energized, causing the de-energization of the starting relays 204 and the test relays 214 and 212 on the first line finder. The power magnets of the free first line finders are thereby de-energized and the free first line finders are arrested. Also the holding magnet 215 of the line finder in question and the common starting relays 216 are de-energized and the relays 252 of the free cords are de-energized, causing the de-energization of the corresponding line finder magnets 261, so that the free second line finders in the group are arrested. Also the test relays 264 and 262 of the cord in question are de-energized. Relay 227 provides over its front contacts the connection of the calling 130

line with the left-hand windings of the repeating coil 229 and the supervisory relay 231, the circuit including sequence switch contacts 232 top and 233 top of sequence switch 220. Relay 231 is energized and provides the short-circuiting of the right-hand high resistance winding of release control relay 121 in a circuit over front contact of relay 231 and contact 107 bottom of sequence switch 100. The energization of sequence switch 330 of the cord in position 4 of sequence switch 250 is hindered through opening of the circuit at contact 108 bottom of sequence switch 100, sequence switch 250 remaining in position 4.

The connection of the test relay 264 to conductor 309 and contact 333 of sequence switch 330, which is in the day time maintained over sequence switch contact 268 of sequence switch 250, is now removed on contacts 109 and 110 of sequence switch 100 and the sequence switch contact 268 is utilized to establish a metallic connection to the trunk line. The metallic circuit is closed over winding of line relay 471, left-hand back contact of cut-off relay 472, contact 470 of sequence switch 460, one wire of trunk line 450, contact 103 bottom of sequence switch 100, upper right-hand winding of repeating coil 229, contacts 111 top and 109 top of sequence switch 100, contact 268 bottom of sequence switch 250, contact 110 top of sequence switch 100, left-hand low resistance winding of relay 121, contact 107 bottom of sequence switch 100, front contact of relay 231, contact 112 bottom of sequence switch 100, relay 242, contact 102 bottom of sequence switch 100, second wire of trunk line 450, contact 469 of sequence switch 460 and back contact of relay 477. Relay 471 in the main exchange and relay 121 in the small exchange are thereby energized. Both windings of the common starting relays 474 are energized in a circuit over the front contact of relay 471, whereas a potential is created at terminal 480 over the individual resistance 473 and back contact of relay 472. The free second line finders of a group of cords in the main exchange are searching for terminal 480 and as soon as the brushes of a line finder of a cord, shown in Fig. 8, reach this terminal relay 664 corresponding to relay 264 is energized and terminal 480 is made busy. Relay 662 corresponding to relay 262 is also energized, the brush carriage is arrested, whereas sequence switch 650, corresponding to sequence switch 250, is energized, started from position 1 and moved into position 4. In position 2₁ of sequence switch 650 sequence switch 620 is also energized, started from position 1 and moved into position 4. When sequence switch 620 is in position 2 a circuit is closed for the energization of relay 627 on the cord and relay

477 on the trunk line including terminal 478 and contact 623 of sequence switch 620. Relay 121 is thereby maintained energized in a metallic circuit over both front contacts of relay 627, contacts 632 and 633 of sequence switch 620, supervisory relay 631 and right-hand windings of repeating coil 629, whereby the relay 627 is energized before the slow-operating relay 477 is able to disconnect the circuit over its back contact so that the relay 121 does not become de-energized during the change over in the circuit. The cord obtains a connection with a free register set and the establishment and supervision of the connection in the main exchange remains the same as for a local call.

When the calling subscriber restores his receiver on the hook, relay 231 is de-energized and the shunt around the high resistance winding of relay 121 is opened, causing the de-energization of relay 631 in the main exchange, and the lighting of clearing-out lamp 645. After the operator receives both clearing-out signals 645 and 635 she depresses the release key 680. During the release of a successfully established conversation the metering battery in the main exchange is connected over contact 623 of sequence switch 620 to terminal 478 and the marginal relays 475 and 476 are energized and connect temporarily the trunk line to a source of alternating current. This causes the energization of relay 122 which, in series with a condenser, is connected in bridge to relay 121. The right-hand winding of relay 123 is thereby energized in a circuit over front contact of relay 122. Since contact 632 is opened in position 15 of sequence switch 620, whereas the metering circuit is closed at sequence switch contact 623 in position 16, relay 121 is de-energized before the metering starts. It provides a circuit for the energization of the left-hand winding of relay 263, including contact 113 top of sequence switch 100, contact 249 of sequence switch 220 and contact 114 bottom of sequence switch 100. The right-hand winding of relay 263 is maintained energized in a holding circuit over its right-hand front contact and sequence switch contact 255 top. Relay 263 closes at its left-hand front contact a circuit for the energization of sequence switch 250 which leaves position 4. In position 5 sequence switch 250 is maintained energized over contact 258 bottom, contact 108 top of sequence switch 100, contact 267 bottom of sequence switch 250, back contact of relay 262 and front contact of relay 252. Sequence switch 250 therefore passes position 5 disregarding the position of sequence switch 330 and moves over positions 8, 9, 10, 11, 12 and 14 into position 17.

When sequence switch 250 passes position 130

6 sequence switch 20 is energized in a circuit over contact 234 bottom, contact 271 top of sequence switch 250 and right-hand back contact of relay 225. Sequence switch 5 220 starts from position 4 and moves into position 5. When sequence switch 250 reaches position 15 sequence switch 220 is again energized in the circuit as described and moves into position 9. Relay 121 is 10 energized in position 9 of sequence switch 220 in a circuit from ground over contact 115 top of sequence switch 100, contact 248 bottom of sequence switch 220, contact 116 top, 112 bottom and 102 bottom of sequence 15 switch 100, one wire of trunk line 450, contact 469 of sequence switch 460, back contact of relay 477 to battery. Sequence switch 220 is energized in a circuit over contact 234 top, contact 117 bottom of sequence 20 switch 100 and front contact of relay 121. Sequence switch 220 starts from position 9. In positions 11 and 14 sequence switch 220 is again energized in the circuit over contact 271 of sequence switch 250. 25 Sequence switch 220 advances into position 1. In position 18 of sequence 220 relay 252 is energized in a circuit over contact 269 top of sequence switch 250, contact 243 bottom of sequence switch 220 and back contact of 30 relay 242. Sequence switch 250 is now energized over front contact of relay 252 and moves into position 18, in which, since the brush carriage of the group selector is in its home position, contact 289 is closed, relay 35 262 is energized and sequence switch 250 is advanced into position 1.

Relay 123 having been energized disconnects on its left-hand back contact the right-hand winding of the non-metering 40 relay 224 from the back contact of relay 227 and connects this winding over the left-hand high resistance winding of relay 123 and contact 255 top of sequence switch 250. Relay 123 maintains thereby its energization, 45 whereas relay 224 remains de-energized. Over the right-hand front contact of relay 123 the circuit for relays 227, 213 and 207 is maintained closed independent of sequence switch 250. When sequence switch 50 220 passes over positions 16+18 the metering battery is temporarily connected at sequence switch contact 223 with terminal 230 and the meter 208 of subscriber line is operated.

If the disconnection is made in the main 55 exchange without metering, relays 476 and 475 remain de-energized so that relays 122 and 123 do not operate. When the release of the cord proceeds, as has been described, sequence switch 250 reaches position 17 and 60 in opening its local contact 251 provides the de-energization of relays 227, 213 and 207. Relay 227 when de-energized causes the energization of the non-metering relay 224 in a circuit over left-hand back contact 65 of relay 227 and sequence switch contact 233.

Relay 224 maintains its energization over its left-hand winding and its left-hand front contact and disconnects on its right-hand contact the connection to the metering battery. When sequence switch 250 reaches position 18 the left-hand winding of relay 224 is short-circuited on contact 272 of sequence switch 250 and relay 224 is de-energized. 70

If a disturbance occurs on the switches the operator in the main exchange is able to 75 hold all the switches used for the connection but to free the calling line by depressing the holdover key on her position together with listening key 639 of the cord. The right-hand winding of relay 625 is 80 thereby energized and the circuit of relay 627 is opened on left-hand back contact of relay 625. Over the right-hand front contact of relay 625 relay 642 is energized and the sequence switch 620 is advanced into 85 position 14. When the quick falling off relay 627 is de-energized a circuit is established over the right-hand back contact of relay 627, including the relay 631, terminal 480, right-hand front contact of relay 472 90 and left-hand winding of slow falling off relay 477. Relays 477 and 472 remain thereby energized, whereas the potential on terminal 480 corresponds to a busy potential so that another second line finder cannot 95 be arrested on this terminal. When the trunk line is opened at the front contacts of relay 627 the release of the switches in the outgoing exchange starts as has been described, whereby sequence switch 250 is 100 advanced into position 17 and the calling subscriber line is made free. Sequence switch 220 is arrested in position 9 since relay 121 remains de-energized. Relay 224 is thereby energized as described but does 105 not influence the calling line since the right-hand armature of relay 224 is disconnected from ground at contact 118 of sequence switch 100. Over the right-hand back contact of relay 227 the right-hand winding of the slow falling off relay 213 is maintained energized in a circuit including relay 231 and terminal 230.

If relay 262 in position 2 of sequence switch 250 is de-energized, which may be 115 the case when two second line finders happen to stay on the same terminal of a calling first line finder and both relays 264 become energized but are not able to maintain their energization after sequence switch contact 120 255 bottom is opened and the high resistance winding is disconnected, relay 263 is energized in a circuit over rest contact of release key 280, sequence switch contact 267 top, back contact of relay 262 and front 125 contact of relay 252. Sequence switch 250 is energized in a circuit over left-hand front contact of relay 263 and sequence switch contact 258, and the sequence switch 250 completes its rotation without starting se- 130

quence switch 220, the circuit of which is opened at the left-hand back contact of relay 263.

When the key 420 is restored sequence switch 400 is energized in a circuit over its contact 406 bottom and rest contact of key 420. Sequence switch 400 starts from position 10 and moves into position 1. Sequence switch 100 is energized in a circuit over contact 105 bottom and contact 402 bottom of sequence switch 400. Sequence switch 100 starts from position 10 and moves into position 11. In opening of contact 403 of sequence switch 400 relay 479 is de-energized and sequence switch 460 is energized in a circuit over its contact 462 top and back contact of relay 479. Sequence switch 460 starts from position 10 and moves into position 11 in which sequence switch 490 is energized in a circuit over contact 492 top and contact 481 bottom of sequence switch 460. Sequence switch 490 moves from position 10 into position 11. Sequence switch 460 cannot move from position 11 if one of the trunk lines controlled by this sequence switch is still engaged in a night connection. In this case the common relay 482 remains energized together with relay 472 of the trunk line. After the trunk lines in question are free on the outgoing end, sequence switch 460 is energized in a circuit over contact 466 bottom and back contact of relay 482. Sequence switch 460 starts from position 11 and moves into position 1 making these trunk lines free for day service. In a similar way sequence switch 490 moves from position 11 if relay 493 of the corresponding trunk line is de-energized.

Sequence switch 100 cannot be restored to position 1 unless the cord is free and its sequence switch 250 is in position 1; when that is the case sequence switch 100 is energized in a circuit over contact 104 bottom and sequence switch contact 255 bottom, sequence switch 100 starts from position 11 and moves into position 1.

In Fig. 7 the control of the operation of a sequence switch 410 similar to sequence switch 400 in Fig. 4 is made automatically over contacts 411, 412 and 413 at the operator's telephone jacks, whereby if the contacts 411, 412, etc., are closed, which is the case when all positions in the exchange are vacant, sequence switch 410 is energized in a circuit over contact 416 top, starts from position 1 and moves into position 10. When one of the positions is occupied and its timing sequence switch similar to sequence switch 350 starts from position 12 and moves into position 1, contact 417, 418 or 419 is closed and sequence switch 410 is energized in a circuit over contact 416 bottom. Sequence switch 410 starts from position 10 and moves into position 1.

In the modification shown in Fig. 6 for

each sixty first line finders in addition to the cords used for day service there are provided a few special second line finders which have access to the same terminals and which are used only during the night service. The special line finders are connected in a similar way to trunk lines which are used in the day for calls outgoing from the main exchange to the small exchange, where they are connected to group selectors. When the night service key 520, corresponding to key 420, is depressed sequence switch 500, corresponding to sequence switch 400, is energized in a circuit over its contact 506 top and contact of key 520. Sequence switch 500 starts from position 1 and moves under the control of its local contact 501 into position 10. Sequence switch 550 of the second line finder used for night service is thereby energized in a circuit over contact 555 bottom and contact 502 top of sequence switch 500. The sequence switch 550 starts from position 1 and moves into position 2. The trunk lines used for night service are at the main exchange under the control of sequence switches as shown in Fig. 4. In position 2 of sequence switch 500 Fig. 5 the circuits which control the sequence switch in the main exchange are closed at contact 503 over a special trunk line, as has been described, and since in the main exchange several trunk lines are controlled by one sequence switch it is essential that a second line finder shall not obtain a connection with a calling first line finder unless the corresponding sequence switch in the main exchange has also prepared the other end of the trunk line. Sequence switch 550 can therefore become energized in a circuit over contact 554 bottom, contacts 540, 541 and 542 of the sequence switches on the corresponding group selectors of the trunk lines if all these sequence switches are in position 1. Sequence switch 550 then starts from position 2 and moves into position 3. The connection to the group selector is then opened at contacts 552 top and 553 top of sequence switch 550. The power magnet 561 of the line finder can now become energized in a circuit over contact 556 bottom of sequence switch 550, back contact of test relay 562 and front contact of common starting relays 216 shown in Fig. 1. When the terminals of the calling first line finder are reached relay 564 is energized in a circuit over sequence switch contact 557 top, right-hand winding of relay 564, sequence switch contact 558 bottom, test brush 560, resistance 217, in Fig. 1, front contact of relay 212 and back contact of relay 213. Relay 564 brings over its front contact its left-hand winding and the winding of relay 562, in parallel to its right-hand winding. The calling terminal is made busy whereas relay 562 is energized, disconnects on its back contact the power magnet 561 and pro-

vides over its front contact and over sequence switch contact 554 top the energization of sequence switch 550. In parallel to the sequence switch the holding magnet 565 5 is connected over contact 559 bottom, the brush carriage is arrested, whereas sequence switch 550 is started from position 3 and moved into position 7. When sequence switch 550 reaches position 5 a circuit is established 10 for the energization of relay 567, relay 213 on the first line finder and the cut-off relay 207 on the subscriber line, including brush 568, left-hand back contact of relay 563 and sequence switch contact 566 top. 15 Relay 567 connects over its front contacts the left-hand windings of the repeating coil 569 and the supervisory relay 571 with the calling line. Relay 571 when energized provides a shunt around the left-hand high resistance winding of the release relay 572. 20 In position 7 of sequence switch 550 the right-hand windings of repeating coil 569 and the relay 572 are connected over sequence switch contacts 552 bottom and 553 25 bottom to the trunk line. Relay 572 as well as relay 471 in Fig. 3 are energized and the call is extended to the main exchange where a connection is established over a cord such as shown in Fig. 6.

30 When the connection is released in the main exchange and sequence switch 620 leaves position 14, opening its contact 632, relay 572 is de-energized and sequence switch 550 is energized in a circuit over contact 555 35 top and back contact of relay 572, sequence switch 550 starts from position 7 and moves into position 14. When on the release of a successfully established conversation sequence switch 620 passes its positions 16 to 40 18 and connects metering battery at its contact 623, relays 475 and 476 are energized and alternating current is connected to the trunk line causing the energization of relay 573 which provides over its front contact a 45 local circuit for the energization of relay 574. In position 14 of sequence switch 550 relay 572 is energized in a circuit from ground over sequence switch contact 575 top, relay 572 both windings, sequence 50 switch contact 552 bottom, one wire of the trunk line and back contact of relay 477 to battery. Sequence switch 550 is then energized in a circuit over contact 554 top and front contact of relay 572. Sequence switch 550 starts from position 14 and moves into 55 position 1. In passing positions 15 to 17 the metering battery 576 is connected at sequence switch contact 566 to the brush 568, and the meter 208 of the subscriber's line is 60 operated. When a connection is released in the main exchange without metering, relay 563 is energized in position 13 of sequence switch 550 in a circuit over contact 575 bottom and back contact of relay 574. Relay 563 maintains itself energized over its right-

hand front contact and sequence switch contact 557 bottom and opens on its left-hand back contact the circuit for relays 567, 213 and 207.

If relay 564 does not remain energized 70 over its left-hand winding after its right-hand winding is disconnected at sequence switch contact 557 top when sequence switch 550 leaves position 3, relay 563 is energized in a circuit over back contact of relay 562 75 and sequence switch contact 556 top. Sequence switch 550 is thereby energized in its position 7 over its contact 559 top and left-hand front contact of relay 563, and the line finder is released, as has been described, 80 without interfering with the calling line. If the switches are held up in the exchange, as has been described, and relay 477 remains energized, the energization of relay 572 is hindered and sequence switch 550 is held 85 in position 14, whereby relay 563 is energized over sequence switch contact 575, as described, and the calling line is made free. The right-hand winding of the slow release relay 213 is thereby maintained energized 90 over brush 560, sequence switch contact 558 top and right-hand back contact of relay 567.

What is claimed is:—

1. In a telephone system, an office, an operator's position therein, a subscriber's line, a selective switch, means for extending the subscriber's line to said switch, a trunk, means for controlling the operation of the selective switch to extend said line over said 95 trunk, a connecting circuit, and means controlled from the operator's position for rendering the selective switch ineffective when the subscriber's line is extended thereto and for extending such line over said connecting circuit.

2. In a telephone system, an office, an operator's position therein, a subscriber's line, a selective switch, automatic switches for extending the subscriber's line to said selective switch, a trunk, a sending mechanism at the operator's position for controlling the operation of the selective switch to extend said line over said trunk, a connecting circuit, and means controlled by the operator for rendering the selective switch ineffective when the subscriber's line is extended thereto and for extending such line over said connecting circuit.

3. In a telephone system, an office, an operator's position therein, a subscriber's line, a selective switch, means for extending the subscriber's line to said switch, a distant office and an operator's position therein, a trunk inter-connecting said offices, means 120 for controlling the operation of the selective switch to extend the subscriber's line over said trunk to the distant office, a connecting circuit outgoing from said first office and terminating in the distant office, and means 125 130

controlled from the operator's position in the first office for rendering the selective switch ineffective when the subscriber's line is extended thereto and for extending such line over said connecting circuit to the operator's position in the distant office.

4. In a telephone system, an office, an operator's position therein, a subscriber's line, a selective switch, automatic means for extending the subscriber's line to said switch, a trunk, means for controlling the operation of the selective switch to extend said line over said trunk, a connecting circuit, an auxiliary device for said selective switch, and means controlled from the operator's position for operating said auxiliary device, said auxiliary device serving to render the selective switch ineffective when the subscriber's line is extended thereto and for extending such line over said connecting circuit.

5. A telephone exchange system comprising a plurality of offices, calling lines terminating at said offices and adapted to be automatically extended to operators at such offices, means under the control of said operators for further extending said calling lines to called lines, concentration controlling means at said offices, means responsive to the operation of said concentration controlling means for automatically extending calling lines terminating in a plurality of said offices to operators at a single office, trunk lines extending between pairs of said offices adapted for normal service therebetween, and means under the control of said concentration controlling means to modify some of said trunk lines so as to eliminate the inter-position of an operator at the office in which a calling line terminates.

6. A telephone exchange system comprising a plurality of offices, calling lines terminating at said offices and adapted to be automatically extended to operators at such offices, means under the control of said operators for further extending said calling lines to called lines, concentration controlling means at said offices, means responsive to the operation of said concentration controlling means for automatically extending calling lines terminating in a plurality of said offices to operators at a single office, trunk lines extending between pairs of said offices, group selector switches at the incoming ends of said trunk lines, contacts of group selector switches at the outgoing ends thereof, line finding switches at said offices, means under the control of said concentration controlling means to modify some of said trunk lines normally serving as outgoing trunk lines from said single office to serve as incoming trunk lines in said office for concentration service, and means for disconnecting a trunk line from its group selector switch when modified for concentration service and for extending calling lines

from line finder switches in the office in which they terminate, to contacts of line finder switches in a concentration office.

7. A telephone exchange system comprising a plurality of offices, calling lines terminating at said offices and adapted to be automatically extended to operators at such offices, means under the control of said operators for further extending said calling lines to called lines, concentration controlling means at said offices, means responsive to the operation of said concentration controlling means for automatically extending calling lines terminating in a plurality of said offices to operators at a single office, trunk lines extending between pairs of said offices, line finder switches for normally extending a calling line to a connecting circuit and thence to an operator, if idle, and special line finder switches having access to the same calling line and adapted to be put in service when said normally operated normal line finder switches are out of service, for extending a calling line to a connecting circuit directly connectable to a trunk line, to said single office, if said trunk line is idle.

8. In a telephone system, an office, an operator's position therein, a subscriber's line, a plurality of selective switches, means for extending the subscriber's line to said switches, a plurality of trunks, means for controlling the operation of the selective switches to extend the subscriber's line over said trunks, outgoing connecting circuits, one for each of said switches, an auxiliary switch for each of said selective switches, means controlled from the operator's position for advancing said auxiliary switches and means operated by the advanced auxiliary switches for rendering the corresponding selective switches ineffective when the subscriber's line is extended thereto and for extending such line over the connecting circuits individual to such selective switches.

9. In a telephone system, an office, a plurality of operators' positions therein, a subscriber's line, a plurality of selective switches, means for extending the subscriber's line to any one of said selective switches, trunk lines, means for controlling the operation of the selective switches to extend the subscriber's line over said trunks, a plurality of outgoing connecting circuits, each individual to certain ones of said selective switches, an auxiliary switch for each of said selective switches, means at each operator's position acting jointly to advance all of said auxiliary switches, and means operated by said auxiliary switches in their advanced condition for rendering the corresponding selective switches ineffective when the subscriber's line is extended thereto and for extending such line over the corresponding outgoing connecting circuit.

10. In a telephone system, an office, an

- operator's position therein, a subscriber's line, a selective switch, automatic means for extending the subscriber's line to said switch, a distant office and an operator's position therein, a trunk line interconnecting said offices, means for controlling the operation of the selective switch to extend the subscriber's line over said trunk to the distant office, a connecting circuit outgoing 10 from the first office and terminating in the distant office, supervisory means at the first office for notifying the operator therein of the condition of a connection, means controlled from the operator's position in the 15 first office for rendering the selective switch ineffective when the subscriber's line is extended thereto and for extending such line over said connecting circuit to the operator's position in the distant office, and means for 20 rendering said supervisory means ineffective when the subscriber's line is extended over said connecting circuit.
11. In a telephone system, an office, an operator's position therein, a subscriber's line, a selective switch, means for extending the subscriber's line to said switch, a second office and an operator's position therein, an outgoing trunk, means for controlling the operation of the selective switch to extend 25 the subscriber's line over said trunk, a connecting circuit extending between said offices normally used for the establishment of connections from the second office to the first office, an auxiliary switch for said 30 selective switch, means controlled from the operator's position in the first office for advancing the auxiliary switch provided said 35 connecting circuit is free at the first office, means operated by the auxiliary switch for rendering said selective switch ineffective 40 when a subscriber's line is extended thereto and for extending such line over the connecting circuit to said second office, and means for extending the connecting circuit to the operator's position in the second 45 office provided the connecting circuit is free at said second office.
12. In a telephone system, an office, an operator's position therein, a subscriber's line, selective switches, means for extending the subscriber's line to said switches, a second office and an operator's position therein, trunks outgoing from said first office, means for controlling the operation of the selective switches to extend said line over said trunks, 50 a plurality of connecting circuits, one for each of said selective switches extending between said offices, an auxiliary switch for each of said selective switches, means controlled from the operator's position in the 55 first office for advancing all of said auxiliary switches provided all the connecting circuits individual to the corresponding selective switches are free at the first office, means controlled by any advanced auxiliary switch 60 for rendering ineffective the selective switch to which it is individual when the subscriber's line is extended thereto and for extending such line over the corresponding connecting circuit to the second office, and means for extending any of said connecting circuits to the operator's position at the second office provided all said connecting circuits are free at the second office.
- In witness whereof, I hereunto subscribe 65 my name this 19th day of August A. D., 1918.

LIPA POLINKOWSKY.
